DENTURE

Sven Gustav Adolf Dahl, Stockholm, Sweden

Application May 31, 1943, Serial No. 489,179
In Sweden May 18, 1942

6 Claims.

(Cl. 32—2)

The present invention relates to an improvement in dental prostheses or dentures of the kind which are intended to be used in such cases, in particular, when a person has lost all or a considerable number of his teeth in his upper jaw or in his under jaw, and which consists of a body of synthetic resin, rubber, or other suitable material, having a shape corresponding to the shape of the jaw, and to which body the artificial teeth are secured. The purpose of the invention is to provide a denture of this type which shall be more securely held to the jaw than what is possible to obtain with the aid of the mouth plates hitherto usually employed.

With this purpose in view the invention is mainly characterized by the said body being provided on the face thereof opposite to the teeth with an approximately ball-shaped or knoblike projection or button, or preferably with a plurality of such projections, which are intended to engage recesses of a corresponding shape formed in the gum tissue of the jaw by surgical incisions therein. These surgical incisions may be very simple and may consist, for instance, of cuts in the form of a cross for each projection on the body of the denture. The projections are then forced into these cuts, in which they are allowed to remain while the cuts heal up. It has been found that during the healing of the cuts, which as a rule is completed after eight or ten days, the gum tissue forms a ball-shaped pocket or socket of a shape corresponding to the projection. In this way the denture gets a good hold in the jaw.

The present improvement may also be used, if desired, in combination with a mouth plate of the ordinary type.

The accompanying drawing illustrates by way of example a denture made in accordance with the present invention. Fig. 1 shows a side view of a portion of the denture, and Fig. 2 shows the same portion viewed from above. Fig. 3 shows to a larger scale a longitudinal section through a portion of the denture with some of the projections thereon. Figs. 4 and 5 show to a still larger scale a side view and a top plan view, respectively, of a modified construction of a projection or button according to the invention.

Fig. 6 shows somewhat diagrammatically a frontal section of the upper jaw and of a denture attached thereto.

Referring to Figs. 1 to 3 of the drawing, 1 denotes a portion of the body of the denture, the shape of which corresponds to the shape of the jaw, and to which the artificial teeth 2 are secured. The body 1 which may be made of syn-

thetic resin, rubber, or any other suitable material, is provided on the face opposite to the teeth 2, that is to say, on the face directed towards the jaw, with a plurality of approximately ball-shaped or knoblike projections or buttons 3. As illustrated in Fig. 3 of the drawing, these projections may be hollow, and each projection may be pressed from a piece of sheet metal, for instance of stainless steel, in such manner that each projection is connected through a narrower neck with two tongues 4 which are moulded into the body 1 in the manner illustrated in Fig. 3, so that in this way the projection is securely held in the body 1. By making each projection 3 with its two associate tongues 4 as a separate part in this manner, the advantage is attained that when making the denture the distances between the projections may easily be varied to suit the shape and size of the denture and other circumstances in each particular case.

In the modified construction illustrated in Figs. 4 and 5, the projection or button 13 comprises a head 14 which is supported by a neck 15 from a base plate 16 to which a piece of wire netting 17 is secured in any suitable manner, as by welding at 18. In this instance the head 14 of the button is provided with a plane annular surface 19 on its lower side. It has been found that the provision of this plane lower surface on the head of the projection or button materially increases the hold of the projection or button in the pocket formed in the gum tissue. The upper side of the head 14 is provided with a plane surface 20 the extension or diameter of which is approximately equal to the diameter of the neck 15 and thus of the inner diameter of the portion of the recess in the gum tissue which corresponds to the neck. The circumferential surface of the head 14 has a well-rounded profile, as illustrated in Fig. 4. It has been found that the head 14 may suitably have an outside diameter of 2.5 mm. and a height of 1.0 to 1.1 mm., and that the diameter of the neck 15 should be approximately 1.0 mm., while the height of the button from the upper surface of the base plate 16 to the upper surface of the head 14 should be approximately 2.4 mm. The base plate 16 should preferably have a diameter somewhat larger than the outside diameter of the head 14. The button is moulded into the body 21 of the denture in such manner that the upper surface of the base plate 16 comes flush with the surface of the body 21, as shown in Fig. 4. The wire netting 17 is thus moulded into the body 21 so that the button is securely held to the latter.

The button 13 is preferably made of a non-corrosive material, such as stainless steel.

When the denture has been completed, it is pressed with the projections 3 or 13, against the jaw with such force that each projection produces a slight mark in the jaw. At each such mark an incision, for instance in the shape of a cross, is then made in the gum tissue to a depth of from 2.4 to 3.3 mm. corresponding to the height of the projections 3 or 13, respectively, after which the projections are forced into these incisions. The patient must then wear the denture in this manner while the incisions are allowed to heal, which as a rule requires a time of eight to ten days. It has been ascertained by experiments that the gum while healing forms around each projection 3 or 13 a pocket of a shape corresponding to that of the projection, and grips around the projections with such force that the denture is securely held to the jaw, but may be removed without difficulty, for instance when the denture need be cleaned.

Fig. 6 shows a frontal section of the upper jaw and of a denture having retention means according to the invention attached thereto. In this figure the retention buttons 13 are of the kind above described in connection with Figs. 4 and 5, and the base plates of said buttons are moulded into the body portion 21 of the denture to which the artificial teeth 2 are secured. The heads and neck portions of the buttons 13 are shown inserted into the abovementioned pockets in the gums 22. The superior maxillary bone is referenced 23.

The constructional form above described and illustrated in the drawing is only to be regarded as an example, and it may, of course, be modified with regard to its details in several ways without departing from the principle of the invention.

I claim:

1. A denture, comprising in combination a body portion having one side shaped to fit the shape of the jaw, artificial teeth secured to said body portion on the opposite side thereof, and at least one substantially ball-shaped or knoblike projection on said firstmentioned side of said body, said projection being adapted to engage a recess of a corresponding shape formed by a surgical incision in the gum tissue of the jaw, for in this manner to securely hold the denture to the jaw.

2. A denture, comprising in combination a body portion made of moulded material and having one

side shaped to fit the shape of the jaw, artificial teeth secured to said body portion on the opposite side thereof, and at least one substantially ball-shaped or knoblike projection on said firstmentioned side of said body portion, said projection comprising a head supported by a neck protruding from said body and a base portion moulded into said body, said projection being intended to engage a recess of a corresponding shape formed by a surgical incision in the gum tissue of the jaw, for in this manner to securely hold the denture to the jaw.

3. A denture as claimed in claim 2, wherein the base portion of the projection consists of tongues 15 attached to the neck of the projection and moulded into the body portion of the denture.

4. A fastening for dentures, comprising a base plate, a neck projecting from said base plate, and a head supported on said neck, said base plate 20 being adapted to be secured to the body of a denture, and said head and neck being intended to engage a recess of a corresponding shape formed by a surgical incision in the gum tissue of the jaw, for in this manner to securely hold the denture to the jaw.

5. A fastening for dentures, comprising a base plate, a neck projecting from said base plate, and a head supported on said neck, said head having an annular plane surface facing the base 30 plate, said base plate being adapted to be secured to the body of a denture, and said head and neck being intended to engage a recess of a corresponding shape formed by a surgical incision in the gum tissue of the jaw, for in this manner to 35 securely hold the denture to the jaw.

6. A fastening for dentures, comprising a base plate, a wire netting secured to the under side of said base plate, a neck projecting from the upper side of said base plate, a head supported 40 on said neck and having an annular plane lower surface facing said base plate, a partially plane upper surface and a rounded circumference, said base plate and wire netting being adapted to be moulded into the body of the denture, and said 45 head and neck being intended to engage a recess of a corresponding shape formed by a surgical incision in the gum tissue of the jaw, for in this manner to securely hold the denture to the jaw.
